UNITED STATES PATENT OFFICE.

JULES ASCHEIM, OF CEDARHURST, NEW YORK.

METHOD OF MAKING COMBINATION-LEGGINGS.

1,274,837.

Specification of Letters Patent.

Patented Aug. 6, 1918.

Application filed March 28, 1918. Serial No. 225,142.

To all whom it may concern:

Be it known that I, JULES ASCHEIM, a citizen of the United States, residing at Cedarhurst, in the county of Nassau and State of New York, have invented certain new and useful Improvements in Methods of Making Combination-Leggings, of which the following is a specification.

My invention relates to combination leggins having an interior resilient foundation which always tends by reason of its resilience to assume a definite and predetermined normal shape, and a face portion which is combined with the said foundation so as to present a smooth and unwrinkled appearance, the connecting means being such, that this combination legging can be freely bent without any wrinkles being formed in the said face portion and without any separation of 20 the foundation and the face portion.

More particularly, my invention is directed to making a combination legging having a foundation consisting of a flexible split leather which has been shaped into a definite and predetermined form, namely the correct and perfect outline of the human leg, and which has sufficient resiliency to always tend to assume this predetermined form, and a face fabric of canvas or similar 30 stretchable fabric which is combined with the leather so as to prevent the formation of wrinkles in the said canvas at any time. As leather merely consists of animal fibers, it is obvious that a number of other materials composed of connected fibers having equivalent properties could be substituted therefor.

A preferred embodiment of my invention is disclosed in the following description and 40 drawings, in which,

Figure 1 is a perspective view showing how my improved legging is put on,

Fig. 2 is a front view of my improved legging showing the same unfastened,

Fig. 3 is similar to Fig. 2 and shows a legging fastened,

Fig. 4 is a perspective view showing how the leather foundation is shaped,

Fig. 5 is a front view showing the connection of a different form of fastener,

Fig. 6 is a front view showing the legging fastened,

Fig. 7 is a central vertical section, somewhat enlarged, of Fig. 6,

Fig. 8 is a section along the line y—y 55 of Fig. 6, and

Fig. 9 is a detail showing the connection of one of the complementary fastening means illustrated in the embodiment of Figs. 5 and 6.

A piece of leather 1 which has been cut substantially into the shape illustrated in Fig. 4 is immersed in water for about thirty minutes at ordinary room temperature, that is between 60 and 70° F. This period of immersion may vary for the different kinds of leather, but thirty minutes is the average time for a piece of rough unfinished leather, whose pores have not been filled up and which may be of a cheaper grade or variety 65 than the ones used for making leather leggings or puttees composed of leather alone.

As a result of this immersion, the pores of the leather take up the water, and it becomes very soft and pliable. It is now 75 stretched into the final shape which is desired, and which should be such so as to fit the leg of the wearer, of which the wooden mold or form 2 is a duplicate.

The leather is well stretched to make it 80 assume its final and predetermined normal shape, and is then secured around the form 2 in its moist and stretched condition by means of the number of tacks 3. The form 2 with the leather 1 fastened as before described, is now dried by means of a current of warm air having a temperature of substantially 85° F.

It is undesirable to dry the leather too 90 quickly as the sudden generation of vapor, if too violent, will enlarge the pores of the leather too much for the purposes of the treatment later to be described. On the other hand, it is desirable to enlarge the pores of the leather to a certain extent so 95 as to fit it for the said treatment. The said temperature of 85° F. is generally satisfactory and as a result of this drying treatment the pores of the leather are substantially enlarged so that they are readily visible 100

with a magnifying glass of low power such as an ordinary reading glass. The surface of the leather also becomes roughened by this treatment and presents a number of minute projections and depressions.

5 After the leather has been thoroughly dried, it is now ready for the next treatment and if the surface is not sufficiently rough, which can be determined by running 10 the tips of the fingers over it, sand paper may be used to give the surface of the leather the desired roughness.

15 The effect of soaking, stretching and drying is to make the leather quite resilient and springy so that it always tends to assume the shape given thereto by this treatment, and fits snugly and neatly around the leg of the wearer.

20 While the leather foundation is still upon the form 2, in dried and stretched condition, its outer side or surface is completely covered with a cement which preferably is a viscous rubber cement dissolved in benzene. This cement should be so viscous that if a pencil 25 or the like be drawn across its surface a noticeable line is formed which remains apparent for several minutes.

At the same time a piece of canvas 4, which has been cut into the shape shown in 30 Fig. 4, has the inner surface thereof also covered with this cement. The film of cement on the leather foundation and the canvas face should be as thin as possible, for the purposes later described.

35 The canvas is so cut that it is stretchable along the line at right angles to the axis of the form 2 and of the legging, and is also stretchable in the perpendicular direction.

40 The leather 1 is kept upon the form 2 at a temperature of between 60 and 70° F. until the cement is dried out so that it has the properties of a somewhat plastic solid so that it requires a perceptible pressure of the finger to cause it to change its shape. The 45 canvas covered with cement as before described is also subjected to the same treatment.

As the cement has not been forced up to the present time into the pores of either the 50 leather or of the canvas, it forms a layer upon their surfaces of a somewhat irregular exterior.

The canvas is now placed symmetrically over the leather upon the form and is 55 strongly pressed thereon, the aforesaid layers of cement being of course in contact.

The cementing is performed by means of a small tool like a knife having a blunt, rounded edge, so that the pressure of the 60 hand produces a considerable pressure per square inch and the leather foundation and the canvas facing are first pressed together along their median lines, that is on the line opposite to the tacks 3. Then the operator 65 presses a part of the canvas adjacent this

median line onto the leather by means of the tool, and strongly stretches the canvas in a direction at right angles to the axis of the legging, and while the canvas is held in this stretched condition, he forces it 70 against the leather with the said tool so that the leather and canvas are cemented together while both are in the stretched condition.

This small tool is applied with a strong 75 pressing and rubbing motion away from this median line, and toward the said tacks 3. The canvas and leather may be cemented together throughout one half and then throughout the other half thereof, and this 80 is preferable, but the cementing may proceed gradually from both sides of the said line, the rubbing and pressing taking place a short distance on one half of the fabric, and then for a short distance on the other half. 85 The small tool is also rubbed on the canvas in a direction parallel to the axis of the legging so as to uniformly cement the canvas to the legging without the formation of any wrinkles. The fabric may thus be also 90 stretched in a direction parallel to the axis of the legging, either by the hand or by this tool.

By the simultaneous rubbing and pressing, the canvas is uniformly stretched, and the 95 cement is so hard that it is forced by the pressure into the pores and inequalities of the leather and into the pores of the fabric so that the tension of the canvas is maintained because the cement does not allow it 100 to spring into its untensed and unstretched condition.

The pressure may be so powerful so as to force the canvas substantially into contact with the little projections on the roughened 105 surface of the leather, the cement being driven into the canvas, and into the little holes on the surface of the leather as well as into the pores of the leather.

After this is done, the canvas is folded 110 around the leather and is stitched along the lines 5 and 6 as shown in Fig. 2, after being cemented at the folds.

It is desirable to cement a piece of non-stretchable tape 7 to the top of the leather 115 before the canvas is applied as this assists in maintaining the leather foundation in its predetermined shape, where the wear and tear are particularly severe.

Of course, the legging is removed from 120 the form before the stitching takes place and the fact that the cement exists in the before mentioned non-flowing condition before the joining takes place is shown by the fact that substantially no cement is squeezed 125 over the margin of the leather.

Since the canvas has been stretched and simultaneously cemented to the resilient leather, which is sufficiently stiff to have a permanent shape like an ordinary leather 130

legging or puttee, the combination legging can be freely bent and manipulated without any wrinkles being formed, and without any separation of the canvas and the leather, 5 and it always springs back to the desired form. This is highly important as a smooth unwrinkled surface is absolutely necessary to give the legging a neat appearance and because the treatment with the rubber cement before mentioned makes the combination legging waterproof, and the fact that the canvas facing always contacts with the leather foundation without any wrinkles, 10 prevents the rubber cement from being chipped off by a blow or the like. The stretching of the canvas is particularly desirable, although not always necessary, because this tends to make it always cling closely to the leather.

15 To fasten the legging, an ordinary strap 9 may be applied which is sewed on at 10 and can be passed on the inside of the legging through slots 11 and 12 and finally be secured to the buckle 14, as shown in Figs. 20 and 3.

Another form of fastening is shown in Figs. 5 and 6. A spring 15 is secured upon the outside of the legging by means of rivets 17, a point 18 being caused to project on 30 the inside through a slot 19 and a strip 20 pasted over the outside of the spring to cover it.

A strip 21 of leather may also be pasted on to the bottom of the inside of the legging so as to prevent it from contracting and to protect the fabric. This is accomplished by causing the leather 21 to project downwardly sufficiently.

The point 18 fits into a socket 191 having 40 a plate 120 so that the point 18 does not rub on the fabric and spoil it.

It is desirable to quickly stitch the fabric and leather together after the cementing in order to prevent the cement from slowly 45 yielding, and thus allow the fabric to lose its tension.

What I claim is:—

1. In the art of making a combination legging having a fabric facing and a foundation of leather sufficiently stiff and resilient to always tend to assume a definite predetermined normal shape similar to the leg of the wearer, those steps in the art which consist in soaking the leather in water until it absorbs some thereof, stretching it into normal shape, maintaining it in normal shape by holding means, drying it while being so maintained in normal shape at a temperature less than the boiling point of water, 55 and cementing the fabric in a stretched condition to said leather before said holding means are released.

2. In the art of making a combination legging having a fabric facing and a foundation of leather sufficiently stiff and resilient

to always tend to assume a definite predetermined normal shape similar to the leg of the wearer, those steps in the art which consist in soaking the leather in water until it absorbs some thereof, stretching it into normal shape, maintaining it in normal shape by holding means, drying it while being so maintained in normal shape at a temperature less than the boiling point of water, 70 and cementing the fabric to said leather before said holding means are released.

3. In the art of making a combination legging having a fabric facing and a foundation of leather sufficiently stiff and resilient to always tend to assume a definite predetermined normal shape similar to the leg of the wearer, those steps in the art which consist in soaking the leather in water until it absorbs some thereof, stretching it into normal shape, maintaining it in normal shape by holding means, drying it while being so maintained in normal shape at a temperature of about 85° F., and cementing the fabric to said leather before said holding means are released.

4. In the art of making a combination legging having a fabric facing and a foundation sufficiently stiff and resilient to always tend to assume a definite predetermined normal shape similar to the leg of the wearer, 85 those steps in the art which consist in stretching the said foundation in a direction at right angles to the axis of the said legging and maintaining it in the said stretched condition, stretching the said fabric in a direction at right angles to the said axis, cementing the said fabric to the said foundation while both are in the said stretched condition, and then releasing the said foundation, the said fabric being permanently 100 maintained in its tensioned condition.

5. In the art of making a combination legging having a fabric facing and a porous foundation sufficiently stiff and resilient to always tend to assume a definite predetermined normal shape, similar to the leg of the wearer, those steps which consist in stretching the said foundation in a direction at right angles to the axis of the said legging, stretching the fabric at right angles 115 to the said axis and connecting it to the said foundation while both are in the same stretched condition by means of a thick cement which is forced into the said porous foundation without substantially spreading 120 sidewise, the said cement being sufficiently strong to maintain the fabric in its tensed condition before it hardens, and maintaining the said fabric permanently tensed.

6. In the art of making a combination legging having a fabric facing and a foundation sufficiently stiff and resilient to always tend to assume a definite predetermined normal shape, similar to the leg of the wearer, those steps in the art which consist in 130

stretching the said fabric in a direction transverse to the axis of the legging and cementing all parts of the said fabric facing to the said foundation while the said facing is so stretched and while the said foundation has substantially the said normal shape, the resilience of the said foundation being so great that it overcomes the tension of the fabric so that the combination legging al-

ways tends to assume the said normal shape, ¹⁰ and the said fabric is always tightly stretched against the said foundation and remains in permanent contact therewith at all parts thereof.

In testimony whereof I hereunto affix my ¹⁵ signature.

JULES ASCHEIM.
